UNITED STATES PATENT OFFICE

2,225,579

COMBINATION VALVE DEVICE FOR GAS DISPENSING SYSTEMS

Loyd J. White, San Antonio, Tex., assignor to
Southern Steel Company, San Antonio, Tex., a
corporation of Texas

Application June 20, 1939, Serial No. 280,209

8 Claims. (Cl. 62—1)

This invention relates to liquefied gas dispensing systems of the general type disclosed in U. S. Patents Nos. 2,121,673 and 2,121,675 and, among other objects, aims to provide a greatly improved fitting or valve assembly wherein all of the safety and dispensing appurtenances, including the necessary pressure reducing regulator and a liquid level gauge, are embodied in a composite unit adapted to be assembled and tested at the factory so that it can be connected to a tank in a single operation. The idea is to provide a greatly simplified fitting embodying certain features of the fitting shown in Patent No. 2,121,675 together with the pressure regulator, but designed for ordinary pressure filling instead of gravity filling and adapted to be connected to a standpipe in such manner that all of the parts are easily accessible from above the ground through the usual protecting casing. Another aim is to eliminate the usual separate manual cut-off valve and utilize the pressure regulator valve for that purpose, thereby further reducing the cost of manufacturing the fitting.

Other aims and advantages of the invention will appear in the specification, when considered in connection with the accompanying drawings, wherein:

Fig. 1 is a fragmentary sectional view, partly in elevation, showing the preferred form of fitting applied to an underground liquefied gas dispensing system;

Fig. 2 is a sectional view taken on the line 2—2 of Fig. 5;

Fig. 3 is a sectional view taken on the line 3—3 of Fig. 4;

Fig. 4 is a sectional view taken on the line 4—4 of Fig. 5; and

Fig. 5 is a top plan view of the fitting shown in Fig. 1.

Referring particularly to the drawings, the improved fitting is shown as being applied to a liquefied gas dispensing system of the general type disclosed in Reissue Patent No. 20,624 and the aforesaid Patents Nos. 2,121,673 and 2,121,675. In such systems, a pressure storage tank 10 is buried in the ground and is partially filled with highly volatile liquefied petroleum gas, commercially known as butane, the liquefied gas being vaporized by absorption of heat from the surrounding earth. The tank is adapted to be filled and the gas dispensed therefrom through a standpipe 11 extending from the top of the tank to a point near the ground level. Instead of employing a unitary combination fitting of the type disclosed in the aforesaid Patent 2,121,675 hav-

ing provisions for gravity filling and a separate pressure reducing regulator adapted to be connected to the service pipe, this invention provides a single combination fitting in which the necessary filling and dispensing appurtenances are combined with one section of the pressure reducing regulator so that all of the necessary appurtenances are attached at one time to the upper end of the standpipe and it is only necessary to connect the service pipe to the pressure regulator casing to complete the installation.

In the present example, the fitting embodies a main hollow body portion 12 having an internally screw threaded opening 13 adapted to be connected to the upper end of the standpipe 11 and 15 the joint is preferably made gastight by means of an ordinary packing nut 14. The hollow body is shown as having chambers 15 and 16 separated by a transverse partition 17 providing an anti-splash baffle and shown as having an opening 18 substantially coaxial with the standpipe. The hollow body is cast integral with the main section 19 of a pressure reducing regulator having a low pressure chamber 20. The lower end of the regulator section is shown as having an integral 25 lateral arm 21 presenting an opening 22 adapted to be slipped over the upper end of the standpipe to provide a more stable support for the fitting and to guide the fitting when it is being screwed on the standpipe. The lower end of the 30 low pressure chamber 20 of the regulator casing is shown as having an opening 23 to receive the usual gas service pipe 24.

The pressure regulator has the usual diaphragm 25 and cap or cover 26 carrying an adjustable compression spring 27 acting on the diaphragm in opposition to a valve lever 28 pivoted at 29 within a vertical conduit 30 in the upper part of the section 19. This conduit is shown as extending through the upper end of the regulator 40 section and is closed by an access plug 31. It communicates with the upper chamber 16 of the body 12 through a conduit 32 extending laterally across the main section 19 and this conduit is closed by means of a plug 33. That portion of 45 the conduit leading into the chamber 16 carries a cylindrical valve sleeve or casing 34 having a gas delivery nozzle 35 on its outer end adapted to be controlled by a valve 36 carried by the lever 28 of the regulator. This sleeve is shown as being seated in the conduit and held in the position shown by means of a set screw 37 extending downwardly through an opening in the main section of the fitting 12. The inside of the sleeve 50 is shown as having a substantially conical valve 55

seat 38 controlled by a winged slug 39 acting as an excess flow check valve and the slug is shown as being retained within the sleeve by means of a pin 40. Incidentally, the sleeve is inclined 5 downwardly so that the excess flow valve will remain open by gravity. However, if desired, an ordinary compression spring may be employed to keep the valve open.

In this instance, the usual manual cut-off 10 valve fitting is dispensed with and the regulator valve 36 is employed to cut off the flow of gas from the tank to the service pipe. To that end, a screw threaded valve operating stem 41 extends through the plug 33 and is adapted to be 15 operated by a hand wheel 42. The inner end of the stem is adapted to engage the rear side of the lever 28 behind the valve 36 and hold it closed. When the valve operating stem is backed off as shown in Fig. 4, the pressure regulator 20 functions in the usual manner to permit the flow of gas generated in the tank through the standpipe and at the desired pressure of, say 6 ounces 25 through the small nozzle 35 into the low pressure chamber 20 of the regulator and out the service pipe. This pressure can be regulated by 30 adjusting the compression spring 27 in the usual manner. Incidentally, the main chamber 20 of the regulator carries the usual pressure relief valve 43 to prevent the pressure from being built up above a safe pressure in the service line.

The main part of the fitting or body 12 is here 35 shown as being provided with a filling branch 44 within which is screwed a hose fitting 45 having a valve seat 46 in its lower end. It is adapted to be closed by an ordinary cap 47. A spring urged check valve 48 cooperates with the seat 46 and has a stem slidably mounted in a spider 49 in the lower portion of the branch 44. A back flow check valve 50 is also carried by the spider, 40 being freely suspended below the spider and it is adapted to close automatically when the hose fitting 45 is removed to replace the valve 48. It will be understood that liquefied gas is pumped or forced under pressure into the tank through 45 the filling branch. The arrangement of the valves in the filling branch may be and preferably are substantially identical with those shown in the aforesaid Patent 2,121,675. The liquefied gas in this case flows through the branch 44 to the lower chamber 15 and is prevented from splashing 50 upwardly into the service outlet by the partition 17 which acts as a baffle. The body 12 also has a second upstanding branch 51 on the opposite side from the branch 44 and carrying a pressure relief valve 52 which is also preferably 55 identical with that shown in said Patent 2,121,675. This branch likewise communicates with the lower chamber 15 of the body as clearly shown in Figs. 2 and 3.

60 The top wall of the body 12 is shown as having an opening 53 to receive a liquid level gauge 54 shown as being of the magnetic type having an operating rod 55 extending through the standpipe into the tank and adapted to be operated by the usual float 56. It will be noted that the gauge is directly above the upper end of the standpipe and the operating shaft 55 extends through the opening 18 in the partition or baffle 17. The gauge is shown as being identical with 65 the one disclosed in the aforesaid Patent 2,121,675. Obviously, a slip-tube gauge, like that shown in Patent 2,121,673, may be employed.

It will be understood that such combination fittings are primarily designed for use in underground systems. In many states, the tanks are

required by the underwriters to be buried in the ground at least two feet below the surface. It is also essential that the tanks be buried below the frost line which, in the coldest climates is more than two feet. The standpipe and the appurtenances in such underground systems are housed within the usual protecting casing 57 having a removable cover 58 as set forth in Reissue Patent No. 20,624.

From the foregoing description, it will be seen 10 that the improved combination fitting embodies all of the necessary safety and dispensing appurtenances and may be quickly assembled by an unskilled laborer. It reduces the number of possible leaky joints to an absolute minimum, 15 having only two connections—one to the standpipe and one to the service pipe. It can be manufactured at a relatively low cost and assembly at the factory insures that the various appurtenances are connected in their proper order and 20 tested for possible leaks. All of the parts are easily assembled and the valves are readily accessible from above, for adjustments and removal or replacement.

Obviously, the present invention is not re- 25 stricted to the particular embodiment thereof herein shown and described. Moreover, it is not indispensable that all the features of the invention be used conjointly, since they may be employed advantageously in various combinations 30 and sub-combinations.

What is claimed is:

1. In a liquefied gas dispensing system having a pressure storage tank and a standpipe 35 connected thereto, a single, composite valved fitting including a hollow body connected to the standpipe and carrying a filling valve, a pressure relief valve; a pressure reducing valve, and a pressure reducing regulator, said regulator having a casing integral with said fitting and being connected to operate said pressure reducing valve.

2. In a liquefied gas dispensing system having a pressure storage tank and a standpipe 45 connected thereto, a single, composite valved fitting including a hollow body connected to the standpipe and carrying a filling valve, a pressure relief valve and a pressure reducing regulator, said regulator having a casing formed 50 integral with the fitting and said fitting having a combined pressure reducing valve and manually operable cut-off valve connected to be operated by said regulator.

3. In a liquefied gas dispensing system having 55 a pressure storage tank and a standpipe connected thereto, a single, composite valved fitting including a hollow body connected to the standpipe and carrying a filling valve, a pressure relief valve and a pressure reducing regulator, said regulator having a casing integral with said fitting and said fitting having a pressure reducing valve connected to be operated by said regulator; and manually operable means to close said pressure reducing valve and cut off the supply of 65 gas.

4. In a liquefied gas dispensing system having a pressure storage tank and a standpipe connected thereto, a unitary fitting comprising a hollow body carrying a filling valve, a pressure relief valve and a pressure reducing regulator, said regulator having a main section extending 70 downwardly adjacent to the standpipe; and an integral lateral brace arm on the lower portion of said casing embracing the standpipe and 75

serving as a guide when the fitting is screwed on the standpipe.

5. In a liquefied gas dispensing system having a pressure storage tank and a standpipe connected thereto, a single, composite valved fitting including a hollow body connected to the standpipe; branches communicating with the hollow interior of the body carrying a filling valve and a pressure relief valve respectively; a gas delivering conduit leading from the upper portion of the fitting carrying an excess flow check valve and a gas outlet nozzle; a pressure regulator casing having a main section integral with said fitting and carrying a pressure reducing valve coacting with said gas nozzle; and a screw-threaded manually operable stem connected to actuate said pressure reducing valve and convert it into a cut-off valve.

6. In a liquefied gas dispensing system having a pressure storage tank and a standpipe connected thereto, a single, composite valved fitting including a hollow body connected to the standpipe; branches communicating with the hollow interior of the body carrying a filling valve and a pressure relief valve respectively; a gas delivering conduit leading from the upper portion of the fitting carrying an excess flow check valve and a gas outlet nozzle; a pressure regulator casing having a main section integral with said fitting and carrying a pressure reducing valve co-

acting with said gas nozzle; means for converting said pressure into a manually operated cut-off valve; and a liquid level gauge on the fitting having a portion projecting through the standpipe.

5

7. As an article of manufacture, a unitary valved fitting for liquefied gas dispensing systems comprising a hollow body carrying a filling valve and a pressure relief valve; a pressure reducing valve and a pressure reducing regulator having a main casing section integral with said body and communicating with the hollow interior thereof, said regulator being connected to operate said pressure reducing valve.

8. As an article of manufacture, a unitary valved fitting for liquefied gas dispensing systems comprising a hollow body carrying a filling valve, a pressure relief valve and a gauge carried by the body; a pressure reducing regulator having a main casing section integral with the body; a gas outlet nozzle in the upper portion of the body discharging into the regulator; an anti-splash baffle in the hollow portion of the body to prevent filling liquid from entering the outlet nozzle; a diaphragm operated pressure reducing valve in the regulator coacting with said outlet nozzle; and manually operable means connected to convert the pressure reducing valve into a cut-off valve.
